UNITED STATES PATENT OFFICE

JABEZ C. NELSON AND WALTER A. PAPWORTH, OF SYRACUSE, NEW YORK, ASSIGNEES
TO SYRACUSE WASHING MACHINE CORPORATION, OF SYRACUSE, NEW YORK, A COR-
PORATION OF DELAWARE

DESIGN FOR A CASING FOR A COMBINED CLOTHES WASHER AND DRIER

Application filed February 6, 1931. Serial No. 38,576. Term of patent 14 years.

To all whom it may concern:

Be it known that we, JABEZ C. NELSON and WALTER A. PAPWORTH, citizens of the United States, residing in the city of Syracuse, in the county of Onondaga and State of New York, have invented a new, original, and ornamental Design for a Casing for a Combined Clothes Washer and Drier, of which the following is a specification, reference being had to the accompanying drawings, forming part thereof.

Fig. 1 is a side perspective view of a casing

for a combined clothes washer and drier showing our new design.

Figure 2 is a perspective view of the opposite side of that shown in Figure 1.

Figure 3 is a top plan view.

We claim:

The ornamental design for a casing for a combined clothes washer and drier substantially as shown.

JABEZ C. NELSON.
WALTER A. PAPWORTH.
